CLAIM

The ornamental design for an under seat storage box for vehicles, as shown and described.

DESCRIPTION

FIG. 1 is a perspective view of the under seat storage box, which embodies the present invention;

FIG. 2 is a front view of the under seat storage box seen in FIG. 1;

FIG. 3 is a rear view of the under seat storage box seen in FIG. 1;

FIG. 4 is a top view of the under seat storage box seen in FIG. 1;

FIG. 5 is a bottom view of the under seat storage box seen in FIG. 1;

FIG. 6 is a left side view of the under seat storage box seen in FIG. 1; and,

FIG. 7 is a right side view of the under seat storage box seen in FIG. 1.

In the drawings, the broken lines depict portions of the under seat storage box that form no part of the claimed design. Shade lines, having a combination of long and short lines, show contour and not surface ornamentation.
